C. HADLER.
SCAFFOLD BRACKET.
APPLICATION FILED NOV. 29, 1918.

1,299,176.

Patented Apr. 1, 1919.

UNITED STATES PATENT OFFICE.

CHRISTIAN HADLER, OF WASHINGTON, DISTRICT OF COLUMBIA.

SCAFFOLD-BRACKET.

1,299,176.

Specification of Letters Patent.

Patented Apr. 1, 1919.

Application filed November 29, 1918. Serial No. 264,716.

To all whom it may concern:

Be it known that I, CHRISTIAN HADLER, a citizen of the United States, residing at 1003 8th St. SE., Washington, District of Columbia, has invented certain new and useful Improvements in Scaffold-Brackets, of which the following is a specification.

This invention relates to improvements in clamps or supports, designed primarily for scaffolds.

The object of the invention is to provide means for quickly and securely clamping a support or brace to a post.

A further object of the invention is to provide a clamp wherein a toggle action is utilized to effect a grip between adjacent parts, the elements being so disposed that the greater the weight supported, the greater will be the clamping efficiency.

20 The invention also comprehends improvements in the details of construction and arrangement of parts which will be herein-after described and particularly pointed out in the claims.

25 In the drawing:—

Figure 1 is a perspective view of my improved clamp.

Fig. 2 is a vertical section of the same; the parts being shown in dotted lines when 30 applying the device to a post.

Fig. 3 is a plan view with parts broken away.

The numeral 1 indicates a U-shape clamping member, and extending across 35 same near its vertical end portion is a bolt 2, on which is mounted to have a slight rocking movement, a shoe jaw 3. Fitting within the free ends of the U-shape clamping member are the free ends of a supporting U-shape member 4, a bolt 5, extending through the free ends of the two members above the horizontal centers, as shown.

A block 6 is confined by the supporting 40 U-shape member near the free ends and to 45 one side the pivot bolt 5, and is secured rigidly in place by rivets or the like, shown at 7. The block 6, is formed with a longitudinal threaded opening 8, disposed below the horizontal center of the U-shape supporting member, and extending therethrough is a bolt 9, the free end of which extends beyond the vertical plane of the bolt 5.

Pivoted on a bolt 10, near the outer end 55 of the U-shape supporting member 4 is a combined brace and clamping member 11, formed for convenience from a single piece

of metal which inclines from the bolt 10, downwardly and is then bent upwardly to form a vertical clamp or jaw 12, the upper end of which is bent outwardly to form a 60 lip 13, which overhangs the bolt 5. The vertical member 12, co-operates with the clamping member 1 when the clamp is applied, as will later appear.

Pivoted on a bolt 14, extending through 65 the U-shape supporting member 4 just in advance of the bolt 10, is a latch 15, the inner end of which is bent upwardly and slightly outwardly, as at 16, to provide a contacting surface 16^a and a finger grip, 70 the contacting surface being slightly in advance of the vertical plane of the vertical clamping member 12. The latch 15, normally rests on the block 6 and is therefore normally at a slight incline with reference 75 to the U-shape supporting member 4 so as to form a wedging action when the clamp is in use.

To operate the clamp, let it be supposed that it be desired to form a scaffold, then the U-shape clamping member 1 is slipped over a post 20, the shoe 3 engaging one edge, and the vertical clamping member 12 engaging the opposite edge. The bolt 9 is of course adjusted to set the vertical member 12 with reference to the shoe, to form sufficient space for the post. The clamp having been adjusted to the desired height on the post, the latch is now thrown down and its contacting surface on the free end engages the edge of the post, and the leverage thrown on the pivot bolt 10 acts to tilt the U-shape supporting member on the pivot bolt 5 and the end of the adjusting bolt 9 is forced into engagement with the vertical member 12 of the brace 11 which results in the shoe being drawn tight against one edge of the post, and the vertical member 12 against the opposite edge of said post, thereby causing a clamping action. When a board or 100 frame 21, is placed on the top of the U-shape supporting member, the weight of same coupled with that of a workman, serves to increase the clamping action on the post. In fact the greater the weight on the supporting member, the more efficient will be the clamping action. Furthermore as the boards 21, rest on the latch, they act to prevent the latch becoming disengaged, should it for any reason work out of engagement 110 with the edge of the post.

Should it be desired to readjust the clamp,

the latch is released and the supporting member 4 is tilted on its pivot, which releases the clamping action and permits free movement of the device.

5 From the foregoing description it will be seen that I have provided means which effectively act to clamp the opposite edges of a post, and when set, the parts coöperate to grip in opposite directions to engage the post, and that the latch prevents movement of the clamp when in latching position. It will be further seen that when weight is placed on the supporting member the clamping action between the clamping elements 10 15 *per se* is materially increased.

By disposing the pivotal connection between the two U-shape members, above a horizontal line drawn through such members, and locating the bolt 9 below this pivotal connection, a locking action between the parts is produced, and is made the more effective when weight is applied to the U-shape supporting member.

While I have shown my improved clamp 25 as applied to a post to support a scaffold board, it is evident its use is in no wise limited in this regard, as it is intended that the device be employed wherever it be desired to clamp members together.

30 What I claim is:—

1. A clamp comprising pivoted members, one of which is provided with a pivoted jaw, an adjustable bolt carried by one member and located out of the plane of the pivot 35 connecting the members to engage said pivoted jaw, and a pivoted latch coöperating with said pivoted jaw to lock the two members in clamped position.

2. A clamp comprising a pair of U-shape 40 members having their ends interfitting one within the other, a pivot bolt connecting the interfitting ends above the horizontal center of said members, a block in one of said members, said block having a threaded 45 opening transverse to and out of the plane of the pivot bolt, an adjusting screw in the threaded opening, and a combined brace and jaw pivoted in one of the members and having its end arranged to be engaged by 50 the adjusting screw, whereby when the member carrying the adjusting screw is tilted in one direction on its pivot the screw will engage the jaw and form with the companion member a grip on a post held therebetween.

3. A clamp comprising a pair of U-shape members pivoted together at their free ends beyond the horizontal center of said members, a screw carried by one of said members and located out of the plane of the pivotal point between said members and at right angle to the same, a jaw mounted on one of the members in front of the screw, and a latch coöperating with the clamping member to hold the device in clamping position. 60

4. A clamp comprising two members pivoted together, one of said members constituting a jaw, a screw carried by the other said member and disposed at right angle to the pivot connecting the said members and projecting beyond the same toward the jaw, a second jaw movably mounted on the member carrying the screw and normally disposed in the path of the latter, and a pivoted latch 70 on the member carrying the screw and adapted to engage the surface of a post engaged by the second mentioned jaw to cause the two jaws to be moved toward each other in clamping position. 75

5. A clamp comprising a U-shape member, a jaw loosely pivoted in said member, a second member pivoted to the free ends of the U-shape member at a point beyond the horizontal center of said members, said second member having a threaded opening transverse to and out of the horizontal plane of the pivot between said members, a screw in the threaded opening, a jaw pivoted to said second member and bent at its free end 90 to lie in the path of the screw, whereby when the jaws engage a post and said second member is tilted on its pivot the screw engages the pivoted jaw and the latter and the first mentioned jaw are drawn together, and a latch pivoted to the second member and adapted to engage the side of the post to tilt said second member to effect the clamping action. 95

6. A clamp comprising pivoted members 100 one of which is provided with a pair of arms and a jaw to embrace a post, a pivoted jaw mounted on the opposite member, and an adjustable bolt carried by the member on which the pivoted jaw is mounted, the bolt 105 being located out of the plane of the pivot connecting the members to engage said pivoted jaw.

In testimony whereof I affix my signature,
CHRISTIAN HADLER.
